UNITED STATES PATENT OFFICE.

ROYAL NORTON CHAPMAN, OF ST. PAUL, MINNESOTA.

FUMIGANT.

No Drawing.

Application filed December 15, 1923. Serial No. 681,009.

To all whom it may concern:

Be it known that I, ROYAL N. CHAPMAN, a citizen of the United States, resident of St. Paul, county of Ramsey, and State of Minnesota, have invented certain new and useful Improvements in Fumigants, of which the following is a specification.

This invention relates to an improved fumigant which overcomes the disadvantages 10 of many of the present fumigants and offers additional advantages. The term fumigant is employed in a generic sense to include substances employed to destroy or kill bacteria, insect and animal life and fungus growths, 15 etc.

Among the substances generally used was carbon disulphide but the great fire hazard attendant upon its use has caused its use to be forbidden by boards of underwriters. 20 Resort has been had to hydrocyanic acid gas. This is a highly toxic gas, insidious and rapid in effect but it is odorless, tasteless, invisible and unfortunate losses of human lives have resulted from its use. Further, this 25 last-mentioned gas is lighter than air and is therefore extremely difficult to apply and direct to the work in hand. In the employment of fumigants, the practical problem as distinguished from the theoretical is usually 30 to fumigate an enclosure whether box, room, barn, house, etc., and, as is well-known, such enclosures are pervious and the fumigant in gaseous form seeps away or leaks before the 35 gas is concentrated to the required toxicity. This is particularly true of the toxics of higher volatilities. This invention provides a fumigant which offers the desired degree of volatility with the necessary toxicity.

The object therefore of the invention is to 40 provide an improved fumigant.

Other objects of the invention will more fully appear from the following description and will be pointed out in the annexed claims.

45 This novel fumigant comprises a combination of chloropicrin (CCl_3NO_2) and carbon tetrachloride (CCl_4). The chloropicrin was developed for war purposes and was primarily adapted for the repelling of human beings. It may be made or obtained in liquid form and is of fair volatility but is not volatile enough for use effectively as a fumigant because it volatilizes at such a relatively slow rate that the usual leakage prevents the desirable concentration of the toxic 50 gas within an enclosure to be fumigated. In

practice, even if the average rate of leakage is somewhat less than the rate of volatilization, too long a time is required for the necessary fumigating concentration; while, if the leakage rate is the greater, the necessary 60 concentration can not be built up. Extensive research and practical tests showed the practical disadvantages of many other substances. Among them was carbon tetrachloride which is obtainable in liquid form and 65 is at present used in what are known commercially as fire extinguishers. This is a liquid whose relative volatility is very high and whose toxicity is relatively low. Hence, this substance was not available as a practical 70 fumigant because, while the desired concentration might be obtained, the toxicity was not great enough. It has been found that a physical mixture of these two liquids in proper proportions produces a fumigant 75 offering the advantages sought and lacking in the disadvantages of each individually. The preferable proportions are half and half. As they are substantially equal in units of weight or volume, it is believed to be relatively immaterial which basis is used although it is convenient to designate equal parts by volume. So far as can be determined there is no chemical reaction between 80 these substances yet this novel compound is 85 similar to carbon-tetrachloride in its volatility and similar to chloropicrin in its toxicity. In other words, a fumigant is provided which substantially has the toxic attribute of chloropicrin and the volatility attribute of carbontetrachloride. Furthermore, the presence of the carbontetrachloride adds its well-known quality of an active 90 fire-extinguishing agent so that the novel 95 fumigant is acceptable to the fire underwriters. This novel fumigant, it may be noted, is particularly efficacious in combating the grain weevil known as *Calendra granaria*.

Having thus described my invention what 100 I claim as new and desire to secure by Letters-Patent, is:

1. A fumigant comprising carbontetrachloride and chloropicrin.
2. A fumigant comprising carbontetrachloride and chloropicrin in equal parts by volume.

In witness whereof, I have hereunto set my hand this fifth day of December 1923.

ROYAL NORTON CHAPMAN.
